(57) **CLAIM**

The ornamental design for a lantern lens, as shown and described.

DESCRIPTION

FIG. 1 is a top perspective view of the lantern lens;
FIG. 2 is a bottom perspective of the lantern lens;
FIG. 3 is a top plan view of the lantern lens;
FIG. 4 is a bottom plan view of the lantern lens;
FIG. 5 is an elevation view of the first side of the lantern
lens;

FIG. 6 is an elevation view of the second side of the lantern
lens; and,

FIG. 7 is a perspective view of the lantern lens attached to
a fence post and cap member.

The broken lines are shown for illustrative purposes only
and form no part of the claimed design.
